SWITCH AND SIGNAL SYSTEM

Archibald G. Shaver, Chicago, Ill.

Application March 2, 1931, Serial No. 519,308

5 Claims. (Cl. 246—219)

This invention relates to a switch and signal system for railways and more particularly to means for operation of such systems and supplying energy therefor.

5 One feature of my invention is the provision of means for generating the power required for the operation of switches and signals at said switches and signals, or for switches and signals in groups.

In the art as heretofore practiced, signals and switches are operated from primary batteries, or from storage batteries of the portable type or stationary type, charged from some convenient source of electrical energy. Oftentimes it has been necessary to run special power lines to the site of the switches and signals to be operated. Such types of construction are not entirely satisfactory in that they are expensive and risk of power failure is involved.

In the examples of my invention disclosed in this application, the systems for switch and signal operation are so designed that the energy required is generated from a local power plant caused to be operated automatically by passing trains, or otherwise.

25 Various other objects, advantages and characteristic features of the invention will be in part apparent and in part pointed out as the description progresses.

In disclosing the specific embodiments of the invention illustrated in detail, reference will be made to the accompanying drawings in which:—

Fig. 1 shows in a diagrammatic manner, the wiring and arrangement of apparatus embodying my invention where one source of energy is used

35 in the operation of the switches and signals.

Fig. 2 while showing practically the same track arrangement as illustrated in Fig. 1, differs in detail of wiring arrangement and provides two sources of power, one for signals and one for

40 switch operation.

Fig. 3 is a diagrammatic showing of a somewhat different form of power plant, including an alternating current generator, where energy of different voltages may be supplied for the operation of switches and signals.

45 Similar reference characters refer to similar parts in each of the several views.

In Fig. 1 is shown a main line stretch of track containing a switch SW normally set for train movements along the track, but adapted to be set for train movements from the main track to the siding. Signal 1 governs trains over the switch along the main track in the direction of the arrow. Signal 3 governs trains from the main track over the switch into the siding. Sig-

nal 2 governs trains along the main track trailing over the switch. Signal 4 governs trains from the siding to the main line. Each signal, as illustrated, is of the light type; and for each the stop indication is designated R and the proceed indication is designated G. The two indications for signal 1 are, therefore, 1R and 1G respectively. Each indication for the other signals is similarly designated.

The switch SW is operated and locked in each the normal and reverse position by mechanism SM. The normal position of the switch is sometimes referred to as the closed position, and the reverse position as the open position. M is a motor operating the mechanism SM. Relay S is a local relay which functions to supply energy to the motor M and to control signal 1. It is normally de-energized and controls back contact 32, front and back contact 23, and back contact 18.

10 Normally de-energized relays P1 and P2 control the respective front contacts 8 and 114 and are operated in circuit with inductors R1 and R2 respectively. Inductors R1 and R2 are so located 15 in the roadside as to be in position for inductive relationship with train carried inductor E as the train passes by.

20 E is a train carried inductor in circuit with the magnet Q, a source of energy G, the thermal relay TH and the switch H. The thermal relay 30 TH normally maintains its contact closed, but, when current passes through its circuit for a prescribed time, the contact opens de-energizing the circuit.

25 T1, T2 and T3 are relays for track circuits in the track stretch. There are other track circuits not shown, for control of the various main line signals, but which are not essential to be specifically described in the description of this invention.

30 Relay T1 is normally energized and controls front contact 52. Relay T2 is normally energized and controls front contacts 29, 38, 51, 11 and 21. Relay T3 is normally energized and controls back contact 75.

35 Relays C1, C3, C2 and C4 are the control relays for the signals 1, 3, 2 and 4 respectively. Control relay C1 is normally energized and controls contacts, front and back 70, and backs 81 and 88. Relay C3 is normally de-energized and controls front and back contact 60. Relay C2 is normally energized and controls front and back contact 83 and back contacts 90 and 62. Relay C4 is normally de-energized and controls front and back contact 77.

40 SB is a circuit controller connected with and

45 55

operated by the switch SW, so that circuit contacts are opened and closed in correspondence with the position of the switch; that is, 42 and 49 are open with the switch in the closed or normal position and closed when the switch is in open or reversed position; and 34 and 57 are closed in the closed or normal position of the switch and open in the open or reversed position of the switch.

10 PB is a circuit controller whose contacts are established in the closed position only when the switch SW is in position and locked. 13 is a hand switch, intended to be used in case the switch SW is in the reverse position and it is desired to return it to the normal position. 110 is a hand switch intended to be operated when, for some reason, it is desired to reverse the switch SW. 113 illustrates a hand operated switch stand which may be used to open and close the switch SW when a train is not in the vicinity or when, for any reason, the power equipment for the switch is out of order.

25 The circuit controller mechanism CK, shown diagrammatically in the drawings, is so constructed that as the motor M is completing its rotation in one direction to open the track switch, the circuit controller CK is moved to complete the motor circuit through conductor 28 for closing the track switch; and when the motor M is 30 near its completion of operating mechanism SM to close the track switch, circuit controller CK again operates to again make the motor circuit complete through conductor 24.

35 Within the frame FR of Fig. 1 is illustrated an automatic power plant for furnishing energy for the operation of the switch SW and the various signals, and relays therefor, controlling over the stretch of track.

40 GE is an engine, preferably the gasoline operated type, direct connected by a coupling CPL to the generator GEN. ST is a starting motor, adapted to be connected by the clutch CL with the engine GE when the motor is started in operation. RHE is a rheostat in the shunt field 45 winding of generator GEN for varying the output voltage of the generator as may be required. RG is a normally de-energized relay connected across the terminals of the generator GEN, and desirably so designed as to be energized when the 50 voltage of the generator GEN has reached the proper point for charging the battery B2 and for furnishing energy to the various circuits. Front contact 103 and back contact 94 are controlled by the relay RG. EB is a battery or a magneto 55 furnishing energy for the ignition of the gasoline engine GE. VAL is an electrolytic cell, valve, or other means, for preventing a flow of current from the battery B2 to the generator GEN, under such circumstances, as when the voltage of the 60 generator GEN is under that of the battery B2. However, the means VAL permits the flow of current from the generator GEN to the battery B2. PS is a relay for the control of the power plant. It is normally de-energized and controls the front 65 contacts 91 and 97.

70 The train carried circuit includes inductor E, conductor 1, electro-magnet Q, conductor 2, generator G, thermal relay TH, conductor 3, switch H normally open, and conductor 4.

75 The circuit for relay P1 includes inductor R1, and conductors 6 and 7. The circuit for relay P2 includes inductor R2 and conductors 106 and 107.

Each of the track relays as T1, T2, etc., are connected to sections of track rails, TR1 and TR2, separated by insulated joints J, with a track bat-

tery as BY also connected to the track rails, furnishing energy in each case.

80 The circuit for control relay C1 comprises common conductor B, contact 29, conductor 30, relay coil C1, conductor 31, back contact 32, conductor 33, contact 34, contact 35 and conductor 44, leading to various other controlling contacts within the block and battery. The circuit for control relay C3 comprises battery B2, conductors 14 and 37, contact 38, conductor 39, relay coil C3, conductor 41, contact 42 normally open, contact 43 and conductors 44, 115, 21 and 15. Control relay C2 comprises common conductor B, conductor 54, coil of relay C2, conductor 55, contact 56, contact 57, conductor 50, contacts 51 and 52 and conductor 53 through other controlling means for the block to battery. Control relay C4 comprises common conductor B, conductor 45, coil of relay C4, conductor 47, contact 48, contact 49 normally open and a connection to conductor 50 thence on to battery including the rest of the circuit for relay C2.

85 The circuit for signal indication 1R includes battery B2, conductors 14 and 72, lamp of 1R, conductor 73, back contact 70 normally open, conductors 71 and 61, back contact 98 normally open, and conductors 27 and 15 to battery. The circuit for signal indication 1G includes battery B2, conductors 14 and 65, lamp of 1G, conductor 66, contact 76, conductors 71 and 61, back contact 90 normally open, and conductors 27 and 15. The circuit for signal indication 3R includes battery B2, conductors 14 and 63, lamp of 3R, conductor 64, back contact 66 normally closed, conductor 61, back contact 90 normally open and conductors 27 and 15. The circuit for signal indication 3G includes battery B2, conductors 14 and 53, lamp of 3G, conductor 59, front contact 66 normally open, conductor 61, back contact 90 normally open and conductors 27 and 15. The circuit for signal indication 40 2G includes battery B2, conductor 14, lamp of 2G, conductor 84, front contact 83 normally closed, conductor 82, back contact 81 normally open, and conductors 89, 26, 27 and 15. The circuit for signal indication 2G includes battery B2, conductor 14, lamp of 2R, conductor 86, back contact 83 normally open, conductor 82, back contact 81 normally open, and conductors 89, 26, 27 and 15. The circuit for signal indication 45 4G includes battery B2, conductor 14, lamp of 4G, conductor 79, front contact 77 normally open, conductor 76, back contact 75 normally open and conductors 74, 27 and 15.

50 When P2 is energized, it closes front contact 114, connecting by conductor 115, between conductors 9 and 27. When relay P1 is energized, it 55 closes front contact 8 connecting through conductor 16 between conductors 9 and 27. The circuit for relay S to energize the same, includes battery B, conductor 14, hand switch 13, front contact 11, conductor 10, coil of relay S, conductor 9 and either front contact 114 or contact 8 closed and conductors 27 and 15 to battery B2. When the relay S is energized, closing the contact 18, then it is included in a stick circuit, same as above disclosed, excepting conductor 17, front contact 70 60 closed and conductor 19 connect between conductors 9 and 15 in parallel with the contacts 114 and 8. The circuit for the motor M to open the 65 switch includes battery B2, conductors 14 and 20, front contact 21, conductor 22, front contact 23 70 75

- closed, conductor 24, circuit controlling device CK, motor M, conductors 25, 26, 27 and 15. The circuit for motor M to close the switch comprises battery B2, conductors 14 and 23, front contact 5 21, conductor 22, back contact 23 closed, conductor 28, circuit controlling device CK, motor M and conductors 25, 26, 27 and 15. The circuit for relay PS to energize the same, includes battery B2, conductor 14, coil PS, conductor 87, back contact 88 closed, conductors 89, 23, 27 and 15. Instead of contact 88 being closed to energize relay PS, contact 62 in parallel circuit with contact 10 88 may be closed, connecting between conductors 27 and 87 via conductor 89.
- 15 The circuit for starting motor ST comprises battery B2, conductors 14 and 66, front contact 91 closed, conductor 92, motor ST, conductor 93, back contact 94 and conductors 25 and 15. The ignition circuit for gasoline engine GE, comprises magneto EB, conductor 99, front contact 97 closed and conductor 98. The circuit for relay RG includes source of energy GEN and conductors 100 and 101. The circuit for charging battery B2 includes conductors 103 and 104, reverse 20 current means VAL, conductors 105 and 14, battery B2, conductors 15 and 55, front contact 103 closed and conductors 102 and 101.

- In Fig. 2 is shown a main line stretch of track containing a switch SW adapted for connecting 30 the main line with the siding. The arrangement of the track, the track circuits, the signals, the mechanism for operating the switch, etc., are practically the same as shown in Fig. 1. Fig. 2 differs from Fig. 1, in general, in that, the switch 35 is not controlled from apparatus on the train and that the power plant is arranged with two sources of energy, one source for the starting motor, signals and relays, and the other source for the operation of the switch.
- 40 As in Fig. 1, the switch is operated and locked in each the normal and reverse position by mechanism SM. M is a motor operating the mechanism SM. Relay S, which is normally de-energized, functions to supply energy to the motor M and to control signal 4, and back contact 100 and front contact 109.

- The track relays are arranged and controlled similarly as described under Fig. 1. Relays C1, C3, C2 and C4 are the control relays for the signals 1, 3, 2 and 4 respectively. Control relay C1 is normally energized and controls contacts front and back 213 and back contacts 225 and 237. Relay C3 is normally de-energized and controls front and back contact 204. Relay C2 is normally 55 energized and controls front and back contacts 223 and back contacts 227 and 229. Relay C4 is normally de-energized and controls front and back contacts 217. SB is a circuit controller connected with and operated by the switch SW, so that the 60 circuit contacts are opened and closed to correspond with the position of the switch; that is, 132 and 201 are closed with the switch in the closed or normal position and open when the switch is in the open or reversed position; 133 and 134 are 65 open with the switch in the closed or normal position and closed when the switch is in open or reversed position; and contact 40 is open with the switch in the normal or closed position and is closed while the switch is in the open or reverse position and while being moved to and from that position. PB is a circuit controller whose contacts are established in closed position only when the switch SW is in position and locked, the same as in the case of Fig. 1.
- 70 75 The hand operated switches 13 and 110 and

the switch stand 113 are used for the same purpose as described in Fig. 1.

The circuit controlling device CK operates in the same manner as described under Fig. 1.

Within the frame FR2 of Fig. 2 is illustrated an automatic power plant furnishing energy for the operation of the switch SW, the starting motor ST1 and the various signals and relays. In this arrangement there is a source of energy, generator GN2 and battery B4, for the switch and another source of energy, generator GN1 and battery B3, for the starting motor, the signals and relays.

GE1 is an engine, preferably a gasoline engine or one of the internal combustion type, connected by couplings CPL with generators GN1 and GN2. ST1 is an electric starting motor adapted to be connected by the clutch CL to the engine GE1. RH1 and RH2 are rheostats in the shunt field windings of the generator GN1 and GN2 respectively for varying the output voltage of these respective generators as may be required. RG1 and RG2 are normally de-energized, connected across the terminals of the respective generators GN1 and GN2 and each is so designed as to be energized when the voltage of its respective generator has reached the proper point for charging its respective battery and for furnishing energy to the respective circuits.

Relay RG1 controls front and back contact 30 129. Relay RG2 controls front contact 149. EB1 is a battery or magneto furnishing ignition energy for the engine GE1. VL1 and VL2 are valves, or means, for preventing the flow of current from the respective batteries B3 and B4 to the respective generators GN1 and GN2, under such circumstances as when the voltage of each generator is under that of its respective battery. However, these reverse current means, VL1 and VL2, permit the flow of current from the respective generators GN1 and GN2 to the respective batteries B3 and B4. As indicated, VL1 and VL2 are on the order of electrolytic cells which pass electric current in one direction, but not in the other direction.

The governor GV is connected on the end of the common shaft for the gasoline engine GE1 and generators GN1 and GN2, or it may be otherwise associated with engine GE1. It is of the ordinary reciprocating type, normally maintaining 50 contact 126 closed, but as the engine GE1 builds up in speed to a prescribed point, the arms of the governor GV straighten out against the tension of the spring 127, opening the contact 126 in the circuit of the starting motor ST1 causing 55 this latter to stop.

PS is a relay for the control of the power plant. It is normally de-energized and controls the front contact 124 and 139.

The circuit for control relay C1 comprises common wire B from battery, contact 171, conductor 178, relay coil C1, conductor 179, back contact 130, conductor 131, contacts 132 and 133 and conductor 184 through other controlling means of the block, as relay of track circuit T4, to the battery. Control relay C3 comprises battery B3, conductors 120 and 185, contact 186, conductor 187, relay coil C3, conductor 128A, contacts 188, normally open, and 189 and conductors 190, 226, 174, 172 and 130 to battery B3. The circuit for control relay C2 comprises common wire B from battery, coil of relay C2, conductor 193, contacts 200 and 201, conductor 195 and contacts 196 and 197, to and through other controlling means of the block to battery. The circuit for control relay 70 75

C4 comprises conductor B from battery, conductor 191, coil of C4, conductor 192, contacts 193 and 194, normally open, thence a connection with conductor 195 of the circuit of relay C2, through 5 other controlling means in the block to battery.

The circuit for signal indication 1R comprises battery B3, conductors 120 and 214, lamp 1R, conductor 215, back contact 213 normally open, conductor 206, back contact 227 normally open and 10 conductors 174, 172 and 130 to battery B3. The circuit for signal indication 1G is the same as above described, excepting that from common conductor 120, conductor 211, lamp 1G, conductor 212 and front contact 213, normally closed, are in 15 parallel with a similar portion of circuit 1R. The circuit for signal indication 3R includes battery B3, conductors 120, 210, lamp 3R, conductor 209, back contact 204, normally closed, conductor 206, back contact 227 normally open, and conductors 20 174, 172 and 130 to battery B3. The circuit for signal indication 3G is the same as that described for 3R, excepting from conductors 120 to 206, conductor 202, lamp 3G and conductor 203 are in parallel with a similar portion of circuit for 25 indication 3R. The circuit for signal indication 2R includes battery B3, conductor 120, lamp 2R, conductor 221, back contact 223 normally open, conductor 224, back contact 225 normally open, conductors 226, 174, 172 and 130 to battery B3. 30 The circuit for indication 2G is the same as that for 2R, excepting for the partial circuit connecting from conductor 120 through lamp 2G, conductor 222 and front contact 223 is in parallel with a similar portion of the circuit for 2R. The circuit 35 for signal indication 4R includes battery B3, conductor 120, lamp 4R, conductor 216, back contact 217 normally closed, conductor 218, back contact 219 normally open, and conductors 174, 172 and 130 to battery B3. The circuit for signal indication 4G is similar to that of signal indication 4R, excepting that from conductor 120, lamp 4G, conductor 220 and front contact 217 are in parallel with a similar part of the circuit for the 40 indication 4R.

45 Circuit closing contacts X1 and X2 are located along the track in such position as to be reached from a train to be closed for the operation of the switch SW when such operation is desired, or these contacts may be arranged to be closed by the 50 dispatcher's selective system or in some other manner. When contact X1 is closed, the circuit established comprises conductors 173 and 160, coil of relay S, conductor 159, hand switch 13, front contact 158, conductor 120, battery B3 and conductors 130, 172 and 171. Similarly when switch 55 X2 is closed, it establishes a circuit comprising conductors 176 and 160, coil of relay S, conductor 159, hand switch 13, front contact 158, conductor 120, battery B3 and conductors 130, 172, 174 and 60 175. When either X1 or X2 is closed, which is presumed to be but momentarily, relay S is energized and when energized, establishes a stick circuit for itself through contact 169 so that the circuit for relay S now comprises battery B3, conductor 120, front contact 158, hand switch 13, conductor 159, coil of S, conductors 160 and 173, front contact 169 and conductors 170, 171, 172 and 130 to battery B3.

65 The circuit for switch motor M for operating the 70 switch from normal to reverse, includes battery B4, conductor 150, front contact 151, conductor 153, front contact 154, conductor 156, circuit operating device CK, motor M and conductors 155 and 147 to battery B4. The circuit for switch motor M for operating switch from reverse to nor-

5 mal, is the same as the next above described circuit, excepting the contact 154 on its back point and conductor 157 are now included in the circuit instead of contact 154 on its front point and conductor 156.

The circuit for relay PS to energize the same includes battery B3, conductors 120 and 230, coil of relay PS, conductor 229, contact 207 normally open and conductors 226, 174, 172 and 130. Connecting in parallel with back contact 207 is a partial circuit from conductor 229 to conductor 174, which includes conductor 208 and back contact 228.

The circuit for the starting motor ST1 includes battery B3, conductors 121 and 122, motor ST1, 15 conductor 123, front contact 124 closed when relay PS is energized, conductor 125, governor controlled circuit contact 126, conductor 128, back contact 129, and conductor 130 to battery. The ignition circuit for engine GE1 includes magneto 20 EB1, conductor 138, contact 139 closed, when PS is energized, and conductor 140. The circuit for relay RG1 includes generator GN1, conductor 135, coil of relay RG1 and conductor 134. The circuit for relay RG2 includes generator GN2, conductor 25 143, coil of relay RG2 and conductor 142. The circuit for charging battery B3, includes generator GN1, conductors 135 and 136, reverse current means or valve VL1, conductors 137, 121 and 120, battery B3, conductor 130, front contact 129 closed 30 when RG1 is energized, and conductor 133.

The circuit for charging battery B4 includes generator GN2, conductors 143 and 144, reverse current means, or valve, VL2, conductor 145, contact 146 closed after the switch SW is out of normal position, conductor 147, battery B4, conductor 148, contact 149, closed when RG2 is energized, and conductor 141.

In Fig. 3 is shown a type of power plant differing from that of Figs. 1 and 2 in that, alternating current is delivered by the generator. GNA is an alternating current generator. GE is the engine driving the generator GNA. ST is the motor for starting the engine. CPL is a coupling connecting the engine with the generator. CL is 45 the clutch, of some of the well known types, operative when the motor ST is started to connect the motor with the engine.

55 GV is a governor of the reciprocating or fly ball type connected with the shaft of the generator, or it may be connected directly with the engine, operative at some prescribed speed to open its contact 242. This prescribed speed is that at which experience shows engine GE is generally apt to operate from its own source of energy.

RG3 is a relay connected with the generator GNA and operative to open its contact 244 when the output of the generator GNA is of a prescribed value. EB is a device controlling the operation of the engine, as, for example, the ignition magneto 60 or battery for a gasoline engine. B5 is a storage battery for the operation of the motor ST, and it may be used for other purposes where electric current of the same characteristics is desirable. B6 is a storage battery floated across the leads 65 from the generator GNA and available to furnish energy to the switch and signals when the generator GNA is not operating. TR is a transformer for producing a voltage of current different from that at the terminals of the generator GNA. VL3 70 and VL4 are rectifiers for changing the alternating current of the generator for charging the batteries B5 and B6 respectively. PS is a relay of the same character and intended to be controlled similarly as is referred to for Figs. 1 and 2. 75

C1, C2 and S are relays of the same sort and similarly connected as indicated in Fig. 2, and contacts 207 and 228 are intended to have the same function as the similarly designated contacts of Fig. 2. Contact 259 is additional to those shown for relay S in Fig. 2, and it will be observed to be in multiple with contacts 207 and 228 to also control relay PS.

The circuit for relay PS of Fig. 3 to energize 10 the same includes battery B5, conductors 253 and 230, coil of relay PS, and then via either of the contacts 207, 228 or 259, or any two or all three of said contacts in multiple, and conductors 174 and 254.

15 The circuit for starting motor ST is identical for that of starting motor ST1 of Fig. 2.

The circuit for charging battery B6 includes 20 generator GNA, conductors 258 and 247, rectifier VL4, conductor 248, battery B6, and conductors 249 and 257.

25 The transformer TR is connected to generator GNA by conductors 247, 258, 250 and 257. The battery B5 is connected to the terminals of the secondary of transformer TR in series with the rectifier VL3.

Operation

The various circuits have been heretofore described. With reference to Fig. 1, assume a train 30 operating on the main track in the direction of the arrow, that is, from left to right:

The switch SW is not operated for this movement. With the train in the block of signal 2, for example in track circuit section for relay T1, contact 52 is opened and relay C2 is de-energized, opening front contact 83 and closing back contacts 83, 90 and 62. The closing of back contact 35 83 changes the circuit for signal 2 so that indication 2R will be displayed for any approaching oppositely bound train. With contact 90 closed, the circuit is complete for displaying the indications 1G and 3R. With contact 62 closed, the circuit is completed energizing relay PS to close its front contacts 91 and 97. The closing of contact 40 91 causes starting motor ST to operate to turn over the engine GE. The closing of contact 97 in the ignition circuit for the engine GE, places the engine in condition to operate by its own power. When the engine GE has speeded up to the point where generator GEN is delivering current 45 sufficient to energize relay RG, front contact 103 is closed and back contact 94 is opened. The closing of front contact 103 places the generator GEN directly in circuit with battery B2 and conductors 50 14 and 15 leading to the various equipments to be operated. The opening of back contact 94 interrupts the circuit and stops the motor ST.

When the train advances into the track section 55 for relay T2, front contacts 29, 38, 51, 11 and 21 are opened. With the opening of contact 29, control relay C1 is de-energized, changing contact 70 from front to back and closing back contacts 81 and 88. The shifting of contact 70 from front to back, changes the indication of signal 1 from 1G to 1R. Relay C2 remains de-energized and indication 3R remains displayed. The making of back contact 81 closes the circuit for signal 2 so that indication 2R is displayed. The circuits for relay S and motor M are open at contacts 11 60 and 21 respectively. The closing of back contact 88, which is in parallel with back contacts 62, also maintains relay PS energized so that the power plant continues to operate. When the train clears the section for relay T1, this relay re-energizes 65 closing contact 52.

As the train passes into the section T4, the track relay for that section (not shown) is de-energized, maintaining control relay C1 de-energized, and relay PS continues energized so that the power plant remains in operation. When the train has passed completely into the section T4, track relay T2 re-energizes closing front contacts 29, 38, 51, 11 and 21, and relay C2 becomes re-energized, changing its contact 83 from back to front and opening its back contacts 90 and 62. 10 By the closing of front contact 83, the display of the indication of signal 2 is shifted from 2R to 2G. The indication of signal 1 is in condition to continue as 1R and of signal 3 as 3R, but as the contact 90 is now open these indications are no 15 longer displayed. The power plant continues in operation because relay PS is still energized due to back contact 88 still being closed.

As the train proceeds, it clears the block of signal 1 so that relay C1 becomes re-energized, 20 shifting its contact 70 from back to front and opening the back contacts 81 and 83. Because of the opening of back contact 81, the indication 2G is no longer displayed. The opening of back contact 88 causes relay PS to become de-energized, 25 opening its front contacts 91 and 97. The opening of front contact 91 is of no immediate effect since the starting motor ST is already stopped. The opening of front contact 97 opens the ignition circuit for engine GE so that the engine and 30 its connected generator GEN now come to a stop. As GEN comes to a stop, relay RG becomes de-energized, opening the generating circuit at contact 103 and closing the starting circuit for motor ST so that the latter is in a condition to begin 35 to operate as soon as contact 91 is again closed. With reference to Fig. 1, assume a train operating over the main track in a direction opposite that indicated by the arrow, that is, from right to left:

Switch SW is not operated for this movement 40 As the train enters the block of signal 1, for example when it is in section T4, the relay for that section, (not shown) is de-energized, causing control relay C1 to become de-energized, shifting its contacts as heretofore explained. With the back 45 contact 81 closed, indication 2G is displayed. With the back contact 88 closed, relay PS is energized, closing its contacts 91 and 97 and the power plant is placed in operation as heretofore described. As the train proceeds into the section 50 of track relay T2, the latter is de-energized, opening its front contacts and control relay C2 also becomes de-energized, shifting its contacts as heretofore explained. Signal indication 2R is now displayed because of back contact 83 being 55 closed. The closing of back contact 90 results in indications 1R and 3R being displayed. Since contact 88 is already closed and as contact 62, in parallel therewith is also now closed, relay PS remains energized and the power plant continues 60 to operate. When the train has passed signal 2, the relay (not shown) in section T4 is re-energized, but relays C1 and C2 remain de-energized since track relay T2 is de-energized.

As the train continues and has passed partly 65 into the section of track relay T1, de-energizing same, the indications 2R, 1R and 3R remain displayed and since back contacts 62 and 88 remain closed, the power plant continues in operation.

When the train has passed from the section of 70 track relay T2, but is still in the section of track relay T1, relay C1 is re-energized so that its contacts are shifted to correspond to the energized condition of the relay. The indication of signal 1 is now shifted from 1R to 1G. The indication 75

3R remains displayed. The indication 2R is not displayed, but it is in condition to be displayed as a stop indication when there is a train approaching the signal 2. The power plant continues to operate since contact 62 remains closed.

As the train proceeds and clears the block of signal 2, relay C2 is again energized, shifting its contacts correspondingly with the result that none of the signal indications are longer displayed and the power plant is stopped because contact 62 being opened, relay PS is de-energized, opening its contacts 91 and 97, the latter stopping the engine GE. With the generator GEN being brought to a condition of rest, relay RG is de-energized, opening its front contact 103 and closing its back contact 104 so that the power plant is again in condition to be operated when a train comes within the limits of its controlling circuits. With reference to Fig. 1, assume a train operating in the direction indicated by the arrow from the main line to the siding:

Switch SW is operated for this movement. With the train in the block of signal 2, as for example the section for relay T4, control relay 25 C2 is de-energized, causing signals 1G and 3R to be displayed. Signals 2 and 4 are in condition to display indications 2R and 4R respectively. As the train proceeds, inductor E comes into inductive relationship with inductor R1. 30 The switch H having previously been closed, the circuit for inductor E is closed so that current is induced into the circuit of inductor R1, energizing relay P1 to close its contact 8 momentarily. The closing of the contact 8 energizes relay S to open its front contact 32, shift its contact 23 from back to front and close front contact 18. The closing of front contact 18 establishes a partial circuit in parallel with that containing contact 8 so that relay S remains energized in a 35 circuit containing its own front contact, such a circuit being in practice, referred to as a stick circuit. The opening of back contact 32 results in control relay C1 being de-energized, operating its contacts so that the indication 1R is immediately displayed in place of 1G. With the contact 23 closed on its front point the circuit is complete so that motor M operates the mechanism SM to reverse or open the switch SW. The first operation of mechanism SM is that of unlocking the switch so that the circuit controller contacts 43, 35, 48 and 56 are opened, placing all of the signals in condition to display the stop indication. When the switch is in the reverse position, the final action of the mechanism SM is to again lock the switch, again closing the circuit controller contacts above referred to. The switch now being in the reverse position, contacts 34 and 57 are opened and contacts 42 and 49 are closed. The closing of contact 42 energizes the control relay C3, shifting its contact 69 from back to front so that indication 3G is displayed showing that the switch is properly set for the train movement into the siding. The indications of signals 2 and 4 remain in the condition of stop, but not displayed, unless there is a train approaching either or both signals.

As the train carried circuit for the inductor E contains a thermal relay or timing device TH, the contact of TH opens after the specified time interval for which TH is set, thereby de-energizing the magnet Q and causing switch H to open its circuit by force of gravity or other means. Thus it will be observed that the circuit for in-

ductor E will not remain closed due to forgetfulness on the part of the train attendant.

As contact 62 is closed when the train entered the block of signal 2, relay PS becomes energized, closing its front contacts 91 and 97 causing the power plant to operate as heretofore has been explained.

As the train proceeds into the section for track relay T2, this relay is de-energized, opening its contacts. The control relays C1, C2 and C4 remain de-energized, due to the now open contacts 28 and 51, and control relay C3 is de-energized due to its circuit being broken at contact 36. The signal indications displayed are 1R, 3R and 2R. Indication 4R is in a condition to be displayed when track circuit for relay T3 is occupied, closing contact 75. With the relay T2 being de-energized, contacts 11 and 21 are opened so that relay S becomes de-energized and the circuit for motor M is opened. As contacts 81 and 62 are closed relay PS is still energized and the power plant remains in operation.

When the train has passed through the section of track for relay T2 into the siding, relay T2 becomes re-energized, closing its contacts. However, as the train entered the section for relay T3, this relay was de-energized, closing its contact 75 and displaying indication 4R. With the rear end of the train clearing the section for T2, indication 4R immediately changes to 4G for a momentary display, before the switch SW starts to operate to return to its closed position, and then returns to the display of indication 4R so long as contact 75 remains closed. Motor M now operates the mechanism SM to move the switch SW from the open to the closed position. This occurs since front contact 21 and back contact 23 are closed. As was before explained, the first function of mechanism SM is to unlock the switch, opening the circuit controller contacts 43, 35, 48 and 56 of circuit controller PB. With the switch being closed, the last function of the mechanism SM is to again lock the switch, again closing the circuit controller contacts of PB. With the switch operating from open to closed position, circuit controller SB is operated so that contacts 42 and 49 are opened and contacts 34 and 57 are closed with the result that control relays C3 and C4 are de-energized and control relays C1 and C2 become energized. With the opening of contacts 88 and 62 the circuit for relay PS is de-energized and the power plant is shut down.

With reference to Fig. 1, assume a train on the siding moving to the main track:

The switch SW is operated for this movement. As the train enters track section for relay T3, this relay is de-energized, closing its back contact 75 so that indication 4R is displayed. As heretofore explained, the circuit for inductor E on the train is closed by switch H so that on coincidence of inductor E with inductor R2, relay P2 is energized to close its contact 114 momentarily. This energizes relay S and causes same to be placed in the stick circuit through its contact 18. The shifting of contact 23 to its front point closes the circuit for motor M causing mechanism SM to function to open the switch. The unlocking and again locking of the switch SW causes circuit controller PB to function as heretofore explained. The operation of the switch SW causes circuit controller SB to function as heretofore explained, with the result that control relays C3 and C4 are energized. Indication 4G is now displayed since track relay 75

T3 is energized. As the indication of signal 3G is in a condition for proceed, it is now displayed since its circuit is closed at contact 90.

The train proceeds on the authority of indication 4G into section for the track circuit T2, relay T2 being de-energized, control relays C1, C3, C4 and C2 are all de-energized and the corresponding signals are in a condition displaying stop, except 4R is not displayed when track section for T3 is not occupied. Since contact 11 is open, relay S is de-energized. Since contact 21 is open, the switch motor M cannot operate. During the time the train is in the section for track relay T2, the power plant is operated as the control relays C2 and C1 are de-energized, closing their respective back contacts 62 and 83, energizing relay PS. The details of operation of the power plant are heretofore explained.

As the train proceeds out of the section for track relay T2 into that for track relay T1, relay T2 again becomes energized, closing its contacts. Since front contact 21 and back contact 23 are now closed, motor M operates the mechanism SM to move the switch SW from the open to the closed position. Consequent with the operation of closing the switch SW, the circuit controllers PB and SB are operated with the result that the contacts of these controllers are returned to normal condition. The signal indications now exist in the condition of stop for signals 4 and 2 with 1G and 3R being displayed. As relay C2 is de-energized and remains de-energized as long as its block is occupied, contact 62 remains closed and relay PS energized continuing the power plant in operation. As soon as the block of signal 2 is cleared, relay C2 becomes energized, opening its back contact 62 and stopping operation of the power plant. All signals are now restored to normal condition.

It will be observed that the switch, the various relays and the signals may be operated direct from battery B2 without the power plant being operated. However, the design of the system should take into account the number of train movements and the amount of energy required by the system for each train movement in such a way that the period of operation of the power plant per day will be sufficient to generate at least as much power as has been consumed per day in the operation of the switches and signals. The function of battery B2 should really be that of floating across the terminals of the generator GEN. A proper design will provide a battery B2 of sufficient size that it will take care of the operation of the plant for a day or two in case the power plant should become inoperative for some reason.

The hand switch 13 is provided for use in emergencies. For example in a case where a train approaching the switch SW may have opened it, and then on it being found necessary that the train not pass over the switch SW, same could be restored to normal position. This is done by operating the hand switch 13 to open the circuit of relay S. Contact 23 being closed on its back point and the circuit complete otherwise, the switch SW will return to its normal position.

Hand switch 110 is provided in parallel with the contacts 8 and 114 for convenience in opening the switch SW in case, for some reason, it is not opened by operation of the apparatus on the train. The closing of switch 110 energizes relay S with the consequent functioning of motor M with the mechanism SM to open the switch.

The switch stand 113 is of the well known type

which will permit of the switch SW being operated by hand in case the switch operating mechanism is inoperative for some reason.

With reference to Fig. 2, assume a train proceeding over the main track in the direction of the arrow E, the switch SW not being operated, for the movement:

As it enters the block of signal 2, for example in the section for track relay T1, control relay C2 is de-energized by reason of contact 197 being opened. The making of back contact 223 places signal 2 in the stop condition. The making of back contact 227 closes the circuit displaying indications 1G and 3R. The closing of back contact 227 causes energization of relay PS. The closing of contact 24 completes the circuit operating starting motor ST1, causing the turning over of engine GE1. The closing of contact 129 in the ignition circuit places engine GE1 in the condition for self operation. Since the generators GN1 and GN2 are coupled to engine GE1, both are operated, GN1 to energize relay RG1, and GN2 to energize relay RG2. When relay RG1 is energized, the circuit is closed at front contact 129 for current to flow to battery B3 to charge the same and also to feed the various circuits through leads 120 and 172. When relay RG2 is energized, the circuit is closed through front contact 149 for charging the battery B4 providing contact 143 is closed, but in this case since the switch has not been operated, contact 146 is open. As soon as back contact 129 is broken, the circuit for the starting motor ST1 is open to stop said motor. However, it is known that when the gasoline engine is rotated to a certain speed, it is usually in condition for self-operation. Therefore, the governor GV, being set to open the contact 126 at a predetermined speed, opens the circuit for starting motor ST1 to stop the same; and this may happen before back contact 129 opens.

When the train is in section for track circuit T2, control relays C1 and C2 are de-energized, by reason of contacts 177 and 186, respectively, being open. All signals are now in condition for indicating stop. By reason of back contact 227 being closed, indications 1R and 3R are displayed. By reason of back contact 225 being closed, indication 2R is displayed. Contacts 207 and 228 are now both closed in parallel, maintaining relay PS energized and the power plant continues operating to charge the battery B3 and furnish energy to the various signals and relays the same as heretofore explained. Since the switch SW has not been operated, generator GN2 is not furnishing energy to battery B4 or to the connected switch circuit.

When the train has passed out of the section for track relay T2 into the section for track relay T4 (not shown), control relay C1 is maintained in a de-energized position, but control relay C2 becomes energized by reason of contact 196 having become closed. Signals 1 and 3 are in a condition for indicating stop, but the indications are not displayed since the circuits for 1R and 3R are now opened at back contact 227. With the energizing of relay C2, contact 223 is shifted from its back point to its front point, therefore, indication 2G is displayed because contact 225 is closed. Since contact 207 is still closed, relay PS is maintained energized and the power plant continues to operate. When the train passes out of the block of signal 1, control relay C1 is again energized. None of the signal indications are now displayed and since back contact 207 is open, relay PS becomes de-energized, opening its con-

tacts 124 and 139 and the engine GE1 is stopped, discontinuing the operation of the power plant.

With reference to Fig. 2, assume a train passing over the stretch of main track in the direction of the arrow W, the switch SW not being operated for this movement:

As the train enters the block of signal C1, for example in track section of T4, relay T4 (not shown) for that section is de-energized, and opens the 10 circuit of control relay C1, de-energizing same. As back contact 225 is now closed, signal indication 2G is displayed. As back contact 207 is now closed, relay PS is energized, closing its contacts 124 and 139. The contact 124 being closed, the 15 motor ST1 operates to start the engine GE1. With the engine GE1 operating, the generators GN1 and GN2 coupled with engine GE1 are also operated to energize their respective relays RG1 and RG2. With relay RG1 energized, back contact 20 of 129 is opened and front contact of 129 is closed. With the opening of back contact 129 the circuit for motor ST1 is opened. With the closing of front contact 129, the circuit is complete for 25 generator GN1 to charge battery B3 and furnish energy to various connected circuits through conductors 120 and 172. Contact 149 is closed in the circuit for generator GN2, but since this circuit remains open at contact 146, because the switch is not open, energy is not supplied to battery B4 and the connected switch circuit. Governor GV 30 operates at a prescribed speed to open contact 126 in the motor circuit to stop the motor ST1.

When the train is in the track section for relay T2, control relays C1 and C2 are both de-energized and all signals are in a condition to give a stop indication, 1R, 3R and 2R being displayed. Since the circuit for relay PS is now closed at both contacts 207 and 228, this relay is maintained energized with the consequent continuance 40 in operation of the power plant as heretofore explained.

When the train is in the section of track relay T1, de-energizing this relay, contact 197 is opened, maintaining control relay C2 in a de-energized condition. Since contact 227 is closed, signal indications 1G and 3R are displayed, relay C1 having become energized by reason of the closing of contact 177 when the train left the section of relay T2. As contact 228 is still closed, relay PS is maintained energized with the consequent continuance in operation of the power plant. When the train passes out of the block of signal 2, all circuits are restored to normal, relay PS is de-energized and the power plant stops 55 operation.

With reference to Fig. 2, assume the train operating from the main track to the siding, the switch SW being operated for this movement:

When the train enters the block of signal 2, relay C2 is de-energized. With contact 223 on its back point, signal 2 is in a condition to display a stop indication. With contact 227 closed, indications 1G and 3R are displayed. With contact 228 closed, relay PS is energized, resulting in the consequent operation of the power plant as has heretofore been explained, for the charging of battery B3 and furnishing energy to its connected circuits.

As the train proceeds, contact X1 is closed, for 70 example by an attendant manually closing the same, or by a dispatcher's selector being operated to close the contact. The closure of contact X1 energizes relay S to close its front contact 169. The closing of this latter contact maintains relay S energized in a stick circuit. With front con-

tact 154 closed, the motor M operates the mechanism SM to open the switch. When the switch mechanism starts to operate, unlocking the switch, circuit controller PB is operated, opening all its contacts. When the switch is in the open position the last operation of mechanism SM, locking the switch SW again closes the contacts of circuit controller PB. The operation of the switch SW also controls the circuit controller SB so that when the switch is in the open position, contacts 182 and 201 are open and contacts 188, 194 and 146 are closed. With the opening of contacts 182 and 201, the circuits for control relays C1 and C2 respectively are opened, and with the closing of contacts 183 and 194, the circuits for 10 control relays C3 and C4, respectively, are closed. With the energizing of relay C3, contact 204 is made on its front point and since contact 213 is made on its back point, indications 1R and 3G are displayed, contact 227 still being closed. The 20 signals are now displayed, authorizing the train to enter the siding.

When the relay S was energized, back contact 180 in the circuit for control relay C1 was broken, de-energizing that relay. As this would occur 25 quickly after contact X1 being momentarily closed, the display of indication 1R in advance of indication 3G could be accepted as an indication to the train that the relay S was functioning to control the opening of the switch.

As contact 146 is now closed, generator GN2 charges battery B4 and furnishes energy to the connected switch circuit.

With the train in the section for relay T2, this latter is de-energized, opening its contacts, so 35 that all control relays are now de-energized and all signals are in a condition for indicating stop, 1R, 3R and 2R being displayed. Contacts 228 and 207 are both closed, and the power plant continues in operation for the generator GN1 to 40 furnish current to battery B3 and its connected circuits and generator GN2 to furnish energy to battery B4 and its connected switch circuit. With the de-energizing of relay T2, contact 158 is opened, causing relay S to become de-energized, 45 making contact 154 on its back point; but the switch motor M cannot operate for the reason that its circuit is now open at contact 151.

When the train has passed through the section for track relay T2 into the siding, track relay 50 T2 becomes energized. With the closure of contact 151, the circuit for motor M is complete through back contact 154, and the mechanism SM functions to automatically return the switch SW to the closed position. When the switch SW reaches the closed position, contact 146 is opened and the operation of generator GN2 in furnishing current to battery B4 and the motor circuit is discontinued. Also, with the energizing of relay T2 and the return of the switch SW to its 60 normal position, closing contacts 182 and 201, control relays C1 and C2 become re-energized so that contacts 207 and 228 are again opened, causing relay PS to become de-energized with the consequent discontinuance of operation of the power 65 plant.

With reference to Fig. 2, assume a train on the siding, proceeding on to the main track, the switch SW being operated for this movement:

Contact X2 is closed momentarily as by an attendant manually closing same, or by a selector operated from a dispatcher's selective system, with the result that relay S is energized, closing its front contact 169. The closing of contact 169 places relay S in a stick circuit. With contact 154 75

made on its front point, the circuit for the motor M is closed and motor M causes mechanism SM to function to open the switch. The functioning of mechanism SM opens the contacts of circuit controller PB until the switch is again in position and locked when the contacts of PB are again closed. Circuit controller SB is also caused to function. With the switch in the open position, contacts 182 and 201 are open in the circuits of signals 1 and 2 respectively, and contacts 188, 194 and 146 are closed in the circuits of signals 3 and 4 and generator GN2 respectively. With the energizing of control relay C4, contact 217 is made on its front point and indication 4G is displayed, due to the fact that the train now has entered the section for relay T3, de-energizing this relay and closing back contact 219. Since control relays C1 and C2 are now de-energized, due to the switch being in the open position, contacts 225 and 227 cause display of indications 2R, 1R and 3G. Contacts 207 and 228 are closed energizing relay PS and consequently placing the power plant in operation, generator GN1 operating to furnish energy to the battery B3 and its connected circuits and generator GN2 operating to furnish energy to battery B4 and its connected switch motor circuit.

When the train proceeds into the section for track relay T2, that relay is de-energized, opening all of its front contacts, with the consequent de-energization of relay S at contact 158, the opening of the motor circuit at contact 151 and the de-energization of all of the control relays. While all signals are in a condition to give the stop indication, only 2R, 1R and 3R are displayed. Since contacts 207 and 228 are closed, relay PS continues to be energized and generators GN1 and GN2 to operate to furnish energy to their respective batteries and circuits.

As the train enters the section for relay T1 and clears the section for relay T2, the latter relay becomes energized. Immediately, when contact 151 is closed, motor M operates to cause mechanism SM to close the track switch SW, restoring contacts of circuit controller SB to normal condition. Control relay C1 now becomes energized, shifting its contact 213 to its front point and causing the display of indication 1G. As the control relay C3 is de-energized, the indication 3R is also displayed. Since contact 228 remains closed, the power plant continues to function, but as contact 146 is open, only generator GN1 is active in furnishing current to its battery B3 and the connected circuits. When the train has proceeded out of the block of signal 2, all circuits are returned to their normal condition with the result that none of the indications are displayed and the power plant ceases to operate.

With reference to Fig. 3, the circuits and the method of operation for the power plant illustrated in Fig. 3 are similar to that for Fig. 2.

Alternating current is available for signals, for example, from leads 255 and 256 of transformer TR. Direct current of the voltage of battery B5 is available, for signals or any other service, from leads 253 and 254. Alternating current of the voltage of the generator GNA is available at the terminals of the generator. Energy for operating various devices, the switch mechanism motor M of Fig. 2 for example, is available from leads 251 and 252.

It will be observed that with the construction indicated in Fig. 3, the battery B6 is not essential. Assume that the switch SW is to be operated for a train, either contact X1 or X2 of Fig. 2 being

closed for that purpose, relay S is energized in a stick circuit closing the contact 259. This causes relay PS to energize setting the power plant in action as heretofore explained. Since either X1 or X2 is closed well in advance of the train reaching the switch SW, the generator GNA is operating and delivering current to leads 251 and 252 in time for the switch to open before the train reaches it. The battery B6 is then only necessary in case a duplicate source of power is desired. For a train entering the main line from the siding, the generator GNA is maintained in operation, as heretofore pointed out, long enough for the switch SW to automatically return to the normal position. In the case of a train entering the siding from the main line, it may be arranged for a contact of relay T3 to maintain relay PS energized till the train has cleared track section for relay T2 and the switch SW has automatically returned to its normal position.

Power plants, such as described in this disclosure, are sufficiently reliable in their operation that signals may be displayed, lamps lighted, and the switches operated direct from the generator terminals without a battery being used as a standby. This feature is of particular benefit for track switch operation since considerable power is required to operate a track switch quickly, and a battery to give that result is expensive in both first cost and maintenance.

The disclosure pertains to a certain unit or section of a track district. In a comprehensive installation a power plant may be used for the operation of every group of signals and switches, and possibly for single switches and single signals. It will be observed in Fig. 2 that I have made provision for other units to get energy from the source disclosed, for example conductor 233 is presumed to lead from a signal (not shown) at the other end of the siding; and conductor 231 is indicated as belonging to a signal (not shown) to the left of the illustration.

While I have made use of the electrolytic cell as a valve in this disclosure to prevent a reverse flow of current from the battery to the generator, I may like to use other means, without departing from the spirit of the invention, to accomplish the same purpose, as the well known reverse current relay, possibly incorporating same as a feature of the RG type of relay shown in the drawings.

While I have disclosed the invention in connection with certain applications and circuit arrangements, it should be understood these are only typical, and furthermore, the complete combination need not be used in all cases. The system, in one phase of the invention, provides means for initiating the generation of power by the passing of a train, regardless of whether said power is in the form of electrical energy for operating a switch, lighting a local station or otherwise, or whether the power is stored in the form of compressed air available for operating switches or other purposes.

What I claim as new is:—

1. In a system for operating a railway switch, a stretch of track containing the switch, mechanism for operating said switch, instrumentalities for controlling said switch, including means operable by a train while within said stretch, and a power plant controlled by said means furnishing energy for said mechanism and comprising a battery, a generator for charging said battery, an engine for driving said generator and circuit controlling means operative by said switch making

said generator effective in charging said battery only when said switch is reversed.

2. In a system for operating a railway switch and signals, a stretch of track containing the switch, mechanism for operating said switch, signals governing traffic within said stretch, instrumentalities for controlling said mechanism and said signals including means operable by a train while within said stretch, and a power plant controlled by said means furnishing energy for said mechanism and signals comprising a battery for said signals, a generator connected therewith for charging said signal battery, a battery for said mechanism, a second generator for charging said mechanism battery, an engine for driving said generators, and circuit controlling means made operative by said switch, rendering said second generator effective in charging said mechanism battery only when said switch is reversed and moving to and from said reversed position.
3. In a railway operating system, the combination comprising a stretch of track with an electrically operated track switch therein, electrically operated signals for governing traffic over said stretch of track, a generator for supplying operating current to said signals and said switch, a track relay associated with the stretch of track, a relay for controlling said signals and said generator, and a circuit for said last relay including contacts of said track relay and contacts controlled in accordance with the position of said track switch.
4. In a railway operating system, the combination comprising a stretch of track including two

electrically insulated track sections, a track relay for each section, an electrically operated track switch in one section, an electrically operated signal for governing the traffic over said stretch of track, a generator for supplying current for said signals and said switch, a relay for controlling the indication of said signal and the operation of said generator, and a circuit for said relay including contacts of both of said track relays.

5. In a track switch operating system, the combination comprising, a stretch of railway track, a plurality of track circuits in said stretch each with a track relay, a track switch in said stretch within the limits of one of said track circuits, a mechanism for operating the track switch, a mechanism circuit controlling the operation of said mechanism for either position of said track switch, a switch control relay which when energized controls said mechanism circuit to open said track switch and when de-energized controls said mechanism circuit to close said track switch, said switch control relay being energized by the closure of a contact controlled at a remote point and de-energized by a contact of the track relay for the track circuit which includes said track switch, a generator for furnishing electric current in the mechanism circuit for the operation of said mechanism, and a generator control relay controlling the operation of said generator to start and stop the same, said generator control relay being energized and de-energized by the operation of the relays of said plurality of track circuits.
